CLAIM

The ornamental design for a bath brush, as shown and described.

DESCRIPTION

FIG. 1 is a top view of the design of the present invention.

FIG. 2 is a bottom view of the design of the present invention.

FIG. 3 is a side view of the design of the present invention.

FIG. 4 is the opposite side of that which is shown in FIG. 3.

FIG. 5 is a front view of the design of the present invention.

FIG. 6 is a rear view of the design of the present invention; and,

FIG. 7 is an enlarged perspective view of the design of the present invention.

The broken line outline representing the brush element is for illustrative purposes only and forms no part of the claimed design.
